SASH HANGER

Chester O. Goserud, St. Paul, Minn.

Application March 2, 1939, Serial No. 259,359

12 Claims. (Cl. 16—172)

My invention relates to sash hangers and has for an object to provide a sash hanger which will prevent rattling of the sash with which it is used.

Another object of the invention resides in providing a sash hanger which can be easily and readily applied so that the sash may be conveniently and quickly hung without undue effort.

Another object of the invention resides in providing a sash hanger which can be readily manufactured and which does not use a great amount of material.

An object of the invention resides in providing a fixed member having a pair of spaced hooks yieldingly held in position and in further providing a pivoted member secured to the sash for engagement with said hooks and held from lateral movement with respect thereto through the said hooks of the fixed member.

Another object of the invention resides in constructing the pivoted member with a tongue adapted to engage between the hooks for guiding the pivoted member into engagement with the fixed member.

Other objects of the invention reside in the novel combination and arrangement of parts and in the details of construction hereinafter illustrated and/or described.

In the drawings:

Fig. 1 is a perspective view of a portion of a window showing a window frame and storm sash and illustrating my invention applied thereto.

Fig. 2 is an elevational view of a portion of the structure shown in Fig. 1 and illustrating the sash in closed position.

Fig. 3 is an elevational sectional view taken on line 3—3 of Fig. 2.

Fig. 4 is a cross sectional view taken on line 4—4 of Fig. 2.

Fig. 5 is a view similar to Fig. 3 showing the method of hanging the sash.

For the purpose of illustrating the application of my invention I have shown a portion of a window frame 10 in Fig. 1 which includes a vertical frame member 11 and a header 12 connected thereto. Within the frame 10 is a sash 13 which includes a stile 14 and an upper rail 15 connected therewith. The pane of glass 16 of the sash 13 is mounted in the stiles and rails of the sash in the customary manner.

My invention comprises a fixed member 17 which is attached to the header 12 of frame 10 and a pivoted member 18 which is attached to the stile 14 of the sash 13. These parts will now be described in detail.

The fixed member 17 is constructed from sheet

metal which is stamped out to provide two semi-circular base portions 21 and 22. These base portions together form a base which I have indicated by the reference numeral 19. Bent outwardly from the diametral edges of the base portions 21 and 22 are two hooks 23 and 24, best shown in Figs. 1 and 3. These hooks are formed with recesses 25 which provide crotches 26 and which form wings 27 extending outwardly beyond said crotches. The wings 27 are constructed with curved outer edges 28 which serve as cams and function in a manner to be presently more fully described. The upper ends of the hooks 23 and 24 are connected together by means of a connector 29 which consists of a portion of the metal 15 from which the entire fixed member 17 is constructed. The connector 29 is relatively narrow and yieldingly connects the two hooks together to permit of a slight springing together of the two hooks. Such action is further facilitated by means of two slits 31 formed in the lowermost portions of said hooks and disposed in close proximity to the base portions 21 and 22. The two hooks 23 and 24 are arranged in diverging relation with the tips 32 of the hooks closer together than the butt portions 33 thereof.

The fixed member 17 is held attached to the header 12 of frame 10 by means of screws 34 which pass through suitable holes in the base portions 21 and 22 and which are situated in close proximity to the connector 29. These screws serve as pivots on which the entire base portions 21 and 22 may pivot to facilitate movement of the butt portions 33 of the hooks 23 and 24 together. The base 19 is further attached to the header 12 by means of other screws 35 which extend through slots 36 formed in the base portions 21 and 22. These slots accommodate movement of the base portions toward and from each other and at the same time hold the base portions firmly seated against the header 12.

The pivoted member 18 is constructed from a strip of sheet metal which is provided with a base 37 resting upon the stile 14 of sash 13. This base is secured to the said stile by means of screws 38 which pass through said base and are screwed into the stile. The pivoted member 18 is constructed with an off-set 39 from which issues a head 41. The head 41 has an opening 42 in it, which opening forms a cross bar 43 and two side 50 arms or lateral portions 44 and 45. The cross bar 43 is constructed with two shoulders 46 and 47 and with a free upper edge 50. The arms 44 and 45 are formed with inwardly facing edges 48 and 49. Issuing inwardly from the center of the cross

5 bar 43 is a tongue 51. This tongue is of a width less than the minimum distance between the two hooks 23 and 24 and is bent outwardly from the plane of the head 41 and toward the window frame 10.

6 While I have described but a single hanger as applied to the sash it can be readily comprehended that the hangers may be used in pairs if desired.

10 The method of using the invention is as follows: In applying the sash, the sash is held at an angle as shown in Fig. 5 and the same elevated until the edge 50 of cross bar 43 engages the curved edges or cams 28 of wings 27 of the hooks 23 and 24. It will be noted when the parts are so disposed that the tongue 51 is disposed between the two wings 27 of the hooks 23 and 24. While so arranged the tongue holds the pivoted member 18 in proper position to be engaged by the hooks. As the sash is elevated the edge 50 slides along the edges 28 and the tongue 51 guides the pivoted member so that, when the shoulders 46 and 47 pass the tips 32 of the hooks 23 and 24 the cross bar 43 will drop into the recess 25 and the shoulders 46 and 47 be received within the crotches 26, as shown in Fig. 1. The distance between the edges 48 and 49 of the side arms 44 and 45 is less than the maximum width across the butt portions 33 of hooks 23 and 24 and greater than the minimum width across the tips 32 of said hooks. As the sash is swung into closing position the edges 48 and 49 engage the curved edges 28 of the wings 27 of said hooks and force the two hooks together. This causes the pivoted member 17 of the hanger to be rigidly held with respect to the fixed member so that rattling of the sash is entirely prevented. As the two hooks are urged together the said hooks flex through the resiliency thereof made possible by the slits 31 and at the same time the base portions of the fixed member swing to accommodate such movement of the hooks. When it is desired to remove the sash, the sash is merely swung outwardly and raised until the cross bar 43 becomes disengaged from the hooks 23 and 24.

15 The advantages of my invention are manifest. The sash hanger is easily applied to the sash and window frame in which the sash is used. The sash hanger may be used with any type of pivoted sash such as storm sash, screen windows or any outwardly opening sash. With my invention rattling of the sash is completely prevented. The device can be constructed from sheet metal by stamping and can thus be economically produced. By means of the tongue used with the pivoted member, the pivoted member is guided into position so that the same readily becomes engaged with the fixed member.

20 Changes in the specific form of my invention, as herein disclosed, may be made within the scope of what is claimed without departing from the spirit of my invention.

25 Having described my invention, what I claim as new and desire to protect by Letters Patent is:

1. A sash hanger comprising a fixed member having two hooks yieldingly held in spaced relation and formed with crotches and a pivoted member formed with shoulders adapted to engage said hooks in the crotches thereof, and with lateral portions adapted to engage said hooks on opposite sides thereof and to urge the same toward one another.

2. A sash hanger comprising a fixed member

30 constructed of sheet metal having a base and two hooks bent outwardly from the base and disposed in spaced relation, means for yieldingly holding said hooks in position, and a pivoted member formed with shoulders for engagement with said hooks and with lateral portions adapted to engage the outermost surfaces of the hooks. 5

3. A sash hanger comprising a fixed member constructed of sheet metal having a base and two hooks bent outwardly from the base and disposed in diverging spaced relation, said hooks being movable toward and from one another, and a pivoted member formed with shoulders for engagement with said hooks and with lateral portions having parallel edges adapted to progressively engage the diverging portions of said hooks and to urge the same together. 10

4. A sash hanger comprising a fixed member constructed of sheet metal and formed with a base and with two hooks bent outwardly from 20 said base, said hooks being yieldingly held in spaced diverging relation and having curved outermost edges, and a pivoted member formed with shoulders for engagement with said hooks and with lateral portions having parallel edges 25 adapted to engage the curved edges of the hooks and to urge the same together upon application of the pivoted member to the fixed member.

5. A sash hanger comprising a fixed member having two separate base portions and hooks extending outwardly therefrom, a connector extending between said hooks and yieldingly holding said hooks in spaced relation and a pivoted member formed with shoulders for engagement with said hooks and with lateral portions adapted 35 to engage the sides of said hooks and to force the same together.

6. A sash hanger comprising a fixed member constructed from sheet metal and formed to provide two separate base portions with hooks bent 40 outwardly therefrom, and further bent to provide a connector connected to said hooks at the outermost edges thereof and yieldingly holding the hooks in spaced relation and a pivoted member formed with shoulders for engagement with 45 said hooks and with lateral portions adapted to engage the sides of said hooks for urging the hooks toward one another.

7. A sash hanger comprising a fixed member constructed from sheet metal and formed to 50 provide two separate base portions with hooks bent outwardly therefrom, and further bent to provide a connector connected to said hooks at the outermost edges thereof and yieldingly holding the hooks in spaced diverging relation, said 55 hooks having outermost curved edges and a pivoted member formed with shoulders for engagement with said hooks and with lateral portions having facing parallel edges adapted to engage the curved edges of said hooks for urging the 60 hooks together upon application of the pivoted member to the fixed member.

8. A sash hanger comprising a fixed member constructed from sheet metal and formed to provide two separate base portions with hooks bent 65 outwardly therefrom, and further bent to provide a connector connected to said hooks at the outermost edges thereof and yieldingly holding the hooks in spaced relation and a pivoted member formed with shoulders for engagement with 70 said hooks and with lateral portions adapted to engage the sides of said hooks for urging the hooks toward one another, and means for pivoting said base portions for swinging movement to accommodate movement of the hooks toward one another. 75

other, said means being positioned in proximity to said connector.

9. A sash hanger comprising a fixed member constructed from sheet metal and formed to provide two separate base portions with hooks bent outwardly therefrom and disposed in diverging relation, and further bent to provide a connector connected to said hooks at the outermost edges thereof and yieldingly holding the hooks in position, said hooks having curved outermost surfaces and being unattached to said base portions throughout the divergent ends thereof to accommodate movement of said hook portions toward one another and a pivoted member formed with shoulders for engagement with said hooks and with lateral portions having parallel edges for engagement with the curved edges of said hooks, said lateral portions urging the hooks together upon application of the pivoted member to the fixed member and causing movement of the base members toward one another and flexing of the free portions of the hooks.

10. A sash hanger comprising a fixed member constructed from sheet metal and formed to provide a base with two hooks projecting outwardly therefrom, said hooks being disconnected from said base at corresponding ends of the hooks to cause the hooks to flex, and a pivoted member formed with shoulders for engagement with said hooks and with lateral portions for engagement with the free ends of the hooks, said hooks restraining lateral movement of the pivoted member.

11. A sash hanger comprising a fixed member having a base provided with flanges issuing outwardly therefrom, said flanges having vertically extending outer edges, said edges of the flanges having recesses therein forming hooks, said hooks

being spaced from one another and free from each other throughout said denoted edges thereof and at the locality thereof, and a pivoted member formed with spaced shoulders adapted to engage said edges of said hooks, said edges guiding the shoulders into said recesses upon raising of the sash and a tongue between said shoulders adapted to enter between aid flanges and to restrain lateral movement of the pivoted member during the aforesaid raising of the sash, said tongue remaining in position between said flanges while the pivoted member is being applied to the fixed member.

12. A sash hanger comprising a fixed member constructed to provide two separate base portions with spaced vertically extending flanges projecting outwardly therefrom, a connector at the upper ends of said flanges, said flanges being free from one another below said connector, said flanges below the connector having hooks formed therein, said hooks having outer edges extending continuously up to the crotches thereof and being free from each other throughout the extent of said edges at the locality of said edges, and a pivoted member formed with two spaced shoulders adapted to engage said edges, said edges guiding the shoulders into engagement with the crotches of the hooks upon raising of the sash, and a tongue on said pivoted member disposed between said shoulders and adapted to enter between said flanges and to restrain lateral movement of the pivoted member during the aforesaid raising of the sash, said tongue remaining in position between said flanges while the pivoted member is being applied to the fixed member.

CHESTER O. GOSERUD.
